UNITED STATES PATENT OFFICE.

PHILIP ROGERS, OF SWANSEA, AND JOHN PLAYER, OF CLYDACH, ENGLAND.

APPARATUS FOR COATING SHEET METAL.

SPECIFICATION forming part of Letters Patent No. 580,802, dated April 13, 1897.

Application filed January 8, 1895. Serial No. 534,268. (No model.)

To all whom it may concern:

Be it known that we, PHILIP ROGERS, residing at Swansea, and JOHN PLAYER, residing at Clydach, near Swansea, in the county of Glamorgan, Wales, United Kingdom of Great Britain and Ireland, subjects of the Queen of Great Britain and Ireland, have invented Improvements in Machinery or Apparatus for Coating Metal Plates or Sheets with Tin, Lead, or other Metals or Alloys, of which the following is a specification.

This invention has reference to improvements in machinery or apparatus of the kind described in the specification of former Letters Patent granted to us, dated March 22, 1892, No. 471,437, for coating metal plates with tin, lead, or other metals or metallic alloys; and it has for its object to further improve the construction and operation of such machinery or apparatus and to further increase the working capacity and economy thereof, as we will now proceed to explain by aid of the accompanying drawings, wherein parts corresponding to similar parts in the former specification are indicated by the same reference-characters.

In the said drawings, Figures 1 and 2 are elevations at right angles to each other and both partly in vertical section, showing our improved machine. Fig. 3 is a plan with part of the pick-up apparatus omitted, and Figs. 4 and 5 are detail views to an enlarged scale. Fig. 6 is an end elevation showing, to an enlarged scale, a modified form of clip suitable for short plates.

A machine of the kind referred to according to the present invention comprises a pot A for the molten coating metal or alloy; a grease-box B, containing two complete sets of finishing-rolls G' G' G³, each roll working in a roll-feeding trough K; two flux-boxes C and C'; two cradles H; a clip-bar d, provided with two sets of spring-clips which receive the plates to be coated two at a time, one through each flux-box, carries them down into the molten metal in the pot A, and delivers them through guide-boxes I and the grease-box into the lower pairs of finishing-rolls G; a pick-up apparatus (marked, collectively, D) provided with two pairs of mechanical fingers and adapted to automatic-

ally remove the finished plates two at a time from the top pairs of finishing-rolls G³ and either deposit them in a suitable rack, as described in our said former specification, or 55 place them on a table or shelf conveniently arranged for the work-people to clean them or place them on a conveyer that will automatically deliver them into a suitable cleaning-machine, and mechanism for operating 60 the several parts mentioned.

Each of the cradles H, the clip-bar d, having slotted ends forming the lateral jaws d' and provided with clips e and springs e', the guide-bars c, with which the jaws d' of the 65 clip-bar d engage, and the side guide-plates g are or may be constructed as described in our said former specification, No. 471,437. Each end of the clip-bar, however, is provided, according to this invention, with an arm d⁴, 70 arranged to project upwardly beyond the corresponding jaw d' and to work against the guide-bars c in order to prevent the spring-clips e e' falling forward; also, the clip-bar d and attached parts are raised and lowered by 75 side levers b, as in our former arrangement, but these side levers are operated in the improved manner we will now explain.

The side levers are moved into their highest position, as shown, by a counterbalance-weight z², which acts through a slotted link or rod b² on a pin b*, carried by a lever-arm b', fixed on a shaft a, on which the said side levers b are also fixed, the said link being adjustably connected, as by a pivoted screw 85 b⁰, to one end of another lever, b³, the other end of which, preferably provided with an antifriction-roller b⁴, is kept in contact with a cam e⁹, fixed on a second shaft e³. As will be seen, the arrangement is such that when 90 the said cam e⁹ is turned in the direction of the arrow the side levers are first allowed to fall and lower the clip-bar d into the most convenient position for inserting the plates into the spring-clips e, in which position it is 95 held for a time while a circular or non-eccentric portion e⁵ of the cam e⁹ is traveling in contact with the antifriction-roller b⁴. Then the cam allows the side levers to descend to their lowest position, so as to permit the top 100 edges of the plates to pass under the V-shaped ribbed casting or guide f', arranged

near the top of the metal-pot A and below the guide-box I, as described in our said former specification, immediately after which the cam, owing to its form, allows the said 5 side levers b to rise under the action of the counterweight z² to their highest position, and thereby insert the top edges of the plates between the lower set of finishing-rolls G.

With our former arrangement of mechanism for operating the side levers the cam or crank employed gave positive motion to the side levers on their downward stroke, the slot in the connecting-rod used in that arrangement permitting the upward stroke to be performed only by the side-lever counterbalance-weight, so that in the event of a plate going wrong no injury was done to the machinery. We find, however, that many machines are injured by tools and other articles being 15 placed on the hot plate in the path of the side levers, which are bent upon coming in contact with these obstructions on their downward stroke. The new arrangement of operating mechanism for the said side levers b provides perfect relief for both up and down strokes, for when the counterbalance-weight z² is raised by the cam e⁹ and lever b³, with roller b⁴, the side levers fall by their own weight only, owing to the pin b⁵, carried by 20 the lever-arm b', working freely in the slot b⁵ in rod b², so that if anything prevents the said side levers moving toward their lowest position the force acting to depress them is only that due to their weight (the clip-bar being 25 almost supported by the molten tin in which it is immersed and quite supported in terne alloy) and the cam will continue to raise the counterbalance-weight z² without damage to any part, as the slot b⁵ is longer than the full 30 stroke of the pin b⁵, carried by the said lever-arm b'. On the other hand, should the side levers or clip-bar from any cause become jammed down it will be only the extra weight of the counterbalance z² above what is required to balance the side levers that tends 35 to bring them up, and the antifriction-roller b⁴ on the lever b³ will be kept from contact with the cam e⁹ altogether or in part, according to the position of the said side lever. In 40 either case no damage can take place.

As will be obvious, the form of the cam e can be varied if required.

A modified form of clip device, according to this invention, suitable for short plates is 45 shown in Fig. 6 and comprises the clip-bar d, with vertical guide-pieces d⁴ and lateral jaws d' to slide on the guide-bars c, bent clips e, each having a shoulder e*, on which a plate to be coated can rest, and a curved free end 50 and bent springs e', each secured to the corresponding bent clips e by a stud e¹⁰, that may conveniently be about one inch long by one-fourth of an inch wide and is arranged to fit 55 in a slot in the spring, which is held in place 60 by a split pin e¹¹ or equivalent means passed through a hole in the stud, as shown, the ar-

angement being such as to permit of the springs being more conveniently reset than in our former arrangement, in which the screws become fixed after being in the molten metal for a short time. Extending along each 70 group of clips is a guide-bar e², which is riveted to each clip. This bar is arranged to work just clear of the front of the ordinary 75 guide ribs or bars M at the back of the molten-metal pot and prevents the clips e falling back too far into the spaces between the said 80 ribs or bars, in which case the plates to be coated could not be placed in the nip of the clips. The vertical guide-pieces d⁴ on the clip-bar serve to prevent the clips falling forward. The bar d is provided at each end with a pin d⁵, by which it is jointed to the 85 links that serve to connect it with the side levers b.

The pick-up apparatus D, which in general construction, arrangement, and operation is similar to that described in our said prior specification, is constructed with coiled springs k⁴ instead of with a weight to give 90 the necessary gripping power to the mechanical fingers n', of which two sets are provided, secured to the vertically-movable operating-rod o² by a cross-bar. The coiled springs k⁴, of which there is one to each movable finger, 95 are arranged in pairs around the pin n², carrying the movable fingers of each set of fingers, Fig. 5, one end of each spring being arranged to bear against a fixed part connected with the fixed fingers and the other end being connected to or arranged to bear against the corresponding movable finger, so as normally to hold the same in its closed position. Each touch device for opening the fingers to grasp and release the plates comprises, according to this invention, a block k², adjustably mounted on the touch-rod K and provided with a hinged latch-piece K', that normally rests on projecting wing-pieces k³ of the block k², the arrangement being such that 100 if by accident or carelessness the touch-bolt i⁰, carried by the extensions i* of the pivoted mechanical fingers n', should get below the said latch-piece the said latch-piece will be lifted upon the said touch-bolt, rising in contact with its under side, so as to permit the said bolt to move freely upward, after which 105 it will fall back into its place on the wing-pieces k³, ready to again open the pivoted fingers at the required time.

The improved machine is designed to increase the output of plates of a low grade, in making which the finishing - rolls are run much slower than when a better-finish plate is required; also, to lessen cost of labor and 110 economize materials as compared with the results obtained from other constructions of apparatus heretofore used for like purposes.

The driving-shaft is connected with and driven by a drive-shaft 5, extending longitudinally of the machine, and cross-shafts 6, carrying worm-gears 7, meshing with one shaft 115 120 125 130

of each pair of rolls G³, the longitudinal and cross shafts being operatively connected by means of the bevel-gears 9.

What we claim is—

- 5 1. In a machine for coating metal plates and sheets, the combination with a molten-metal pot, and fixed vertical guide-bars therein, of the vertically-movable plate-carrier consisting of the horizontal bar d adapted at its end 10 to slide on said guide-bars and provided with spring-clips e, e' and at its ends with a vertical arm d⁴ arranged to extend upward above the guided ends of the guide-bar and to work against said guide-bars c substantially as herein described for the purpose specified.
- 15 2. In a machine for coating metal plates and sheets, the combination with a pot A having ribs M at the back thereof, and fixed vertical guide-bars c, of a vertically-movable plate-carrier comprising a horizontal bar d adapted to slide vertically on said guide-bars and provided with vertical guide-pieces d⁴ at each end arranged to work against said guides c and with spring-clips each consisting of a bent 25 clip e having a shoulder e* and a curved free end, a bent spring e', a stud e¹⁰ secured to said bent clip and extending through a slot in said bent spring, and a pin e¹¹ extending through said stud on the outer side of said bent spring, and a guide-bar e² extending along and secured to said bent clips e and arranged to work just clear of the ribs M on said pot substantially as herein described for the purpose specified.
- 30 35 3. In a machine for coating metal plates or sheets, the combination with the molten-metal pot, of a vertically-movable plate-carrier, levers from which said carrier is suspended, a weight-carrier connected with said levers so that the one can move vertically to a limited extent independently of the other, a counterbalance-weight supported by said weight-carrier and adapted when suspended by said levers, to raise the same and attached 40 plate-carrier, and means for raising and lowering said weight-carrier and weight at the required times, substantially as herein described for the purposes specified.
- 40 45 50 55 4. In a machine for coating metal plates or sheets, the combination with the molten-metal pot, of a vertically-movable plate-carrier, levers from which said plate-carrier is suspended, a lever-arm in connection with said levers, a rod connected by a pin-and-slot connection with said lever-arm and carrying a counterbalance-weight adapted when the

rod is suspended from said lever-arm to raise said levers and attached plate-carrier, a lever adjustably connected with said rod, and a cam for operating said rod and attached parts, substantially as herein described for the purposes specified.

5. In a machine for coating metal plates or sheets, a pick-up apparatus having pairs of mechanical fingers n' whereof the movable 65 fingers of each two pairs of fingers are carried by a pin n² and provided with arms or extensions i* connected by a pin i⁰, the said pin n² being provided with a pair of coiled springs k⁴ each having one of its ends arranged to bear against a fixed part connected with the fixed fingers and the other end arranged to normally hold the corresponding pivoted finger in the closed position when the said pin i⁰ is free, and a tappet arranged to 70 open the pair of connected movable fingers at the required times against the action of said springs, substantially as herein described.

6. In a machine for coating metal plates or sheets, the combination with a pick-up apparatus having pairs of mechanical fingers n' adapted to automatically remove coated plates from the coating apparatus, of tappets arranged to open said fingers and each comprising a touch-rod k, a block adjustably 80 mounted on said rod and provided with a projecting part or parts, and a latch-piece hinged or pivoted to said block and normally resting on the projecting part or parts thereof, substantially as herein described for the purpose 90 specified.

7. A metal-coating machine comprising an elongated dipping-pot, a plurality of plate-carriers for said pot, a driving-shaft extending throughout the length of the pot above 95 and at one side thereof, counter-shafts at each end of the driving-shaft meshing therewith and extending over opposite ends of the pot, two sets of rolls situated over the pot and extending longitudinally thereof, the adjacent 100 ends of the shafts and rolls having intermeshing gears, and plate-carriers operatively connected with said driving-shaft, substantially as described.

In testimony whereof we have signed our 105 names to this specification in the presence of two subscribing witnesses.

PHILIP ROGERS.
